JACOB DAVIS, OF UNIONTOWN, PENNSYLVANIA.

SPRING-MOTOR ESCAPEMENT.

1,212,786.

Specification of Letters Patent. Patented Jan. 16, 1917.

Application filed January 19, 1916. Serial No. 72,933.

To all whom it may concern:

Be it known that I, FRANK MAGIDSON, a citizen of the United States, and resident of Brownsville, in the county of Fayette and State of Pennsylvania, have invented certain new and useful Improvements in Spring-Motor Escapements, of which the following is a specification.

The object of this invention is to provide an improved and highly efficient spring motor escapement, whereby the motor may be utilized for actuating an oscillating or other reversely moving body, the arrangement being such that the operation of the escapement is stopped and remains quiescent upon stopping the movement of the oscillating body, but is resumed upon again imparting motion to the body, the momentum of the latter thus operating to keep the escapement mechanism in motion.

Figure 1 is a longitudinal section of the spring motor and escapement mechanism, and Fig. 2 is a top plan view of the same. Fig. 3 illustrates one of the escapement dogs in detail. Fig. 4 is a view of the escapement shown in Fig. 2, being drawn to a larger scale. Figs. 5 and 6 are sectional elevations taken at right angles to each other, illustrating the modified application of the escapement mechanism.

Referring to the drawings, the spring motor and escapement mechanism are preferably inclosed in a suitably supported casing 7, the motion being transmitted by means of a link 8 to the part to be oscillated, the link being connected to the escapement mechanism at 9.

The spring element of the motor may be variously embodied. As here shown, it consists of an elongated coiled spring 10 which is adapted to be wound on spool 11, the latter secured to shaft 12 extending longitudinally through casing 7 with the projecting extremities thereof adapted to removably receive a crank 13 whereby the motor may be wound up from either end of the casing. As shown in Fig. 1, one end of the spring is secured at 14 to the spool and its opposite end at 14' to a fixed bracket 15.

In the adaptation shown in Fig. 1 the ratchet wheel 16 of the escapement mechanism is journaled on post 17, the latter supported from beneath by bracket 18 and from above by bridge 19 which overhangs the ratchet wheel, said bracket and bridge being

suitably secured to the casing. A beveled pinion 20 at the under side of the ratchet wheel meshes with the larger gear wheel 21 secured to spool 11 and shaft 12. If this reduction gearing is not desired the ratchet wheel 16 may be directly connected to shaft 12 as in Figs. 5 and 6, in such case a spider-like frame 22 being arranged transversely within casing 7 in lieu of bridge 19 for supporting the escapement levers presently to be described.

Projecting from bridge 19 (or from spider 22) are the two posts 23 arranged at diametrically opposite sides of the axial center of ratchet wheel 16, and fulcrumed and adapted to oscillate on these posts are the two levers 24 and 25 having their adjacent ends jointed together at 26 whereby the free portions of the levers which extend outward over opposite portions of the ratchet wheel are adapted to operate simultaneously. Pivoted to the under or inner side of lever 24 is dog 27 of bell-crank form and similarly mounted on lever 25 but in reverse position is the like dog 28. One arm of each dog is shaped to have ratchet engagement with the teeth of wheel 16 while the other and inwardly extending arm located beneath or back of the lever is notched as indicated at 29. Secured to fulcrum posts 23 is a substantially straight spring 30 with one arm 31 thereof extending outwardly over lever 24 and downwardly through an aperture 24' in the latter where it engages extremity 29 of dog 27. And similarly, the other spring arm 32 overhangs lever 25 and is extended through aperture 25' thereof and secured to extremity 29 of dog 28. Apertures 24' and 25' are materially larger than the spring extending therethrough and afford the levers and spring arms relative movement in order to effect the escapement, as will be presently described. Lever 24 is extended for the pivotal connection 9 with link 8, whereby the escapement mechanism is connected to the oscillating body, in the present instance a cradle.

Operation: The dogs 27 and 28, one or the other, operate to lock the ratchet wheel when the mechanism is quiescent, also when the motor is being wound up, during the winding operation the ratchet wheel slipping freely past the holding dog, as will be understood. The spring arms 31 and 32 oppose deflection from their fixed normal straight-

line position, but the deflection thereof resulting from the oscillations of levers 24 and 25 operate to move dogs 27 and 28 on their pivots either into or out of engagement with the ratchet wheel, determined by the direction each spring arm is deflected.

With the escapement mechanism in the position shown in Figs. 2 and 4, the ratchet is held by dog 28, the movement of lever 25 10 into the position shown resulting in causing spring arm 32 to swing dog 28 into engagement with the ratchet, and at the same time the movement of lever 24 has caused spring arm 31 to oscillate the oppositely positioned dog 27 in a direction to release its hold on the ratchet wheel. Now with the parts in the position shown in Fig. 2, if the cradle body is started to swinging, the first effective oscillation will move lever 24 toward the top 15 of Figs. 2 and 4, and joint 26 will result in similarly moving the free portion of lever 25. But as dogs 27 and 28 are reversely positioned, the described movement of lever 25 will cause spring arm 32 to turn dog 28 20 out of engagement with the ratchet wheel, while the simultaneous movement of lever 24 will, through the medium of spring arm 31, have an opposite effect on dog 27. Hence, while the hold of dog 28 is being relaxed 25 and finally released, dog 27 is being moved into position to engage the next approaching tooth of the ratchet wheel, so that the reverse or backward oscillation of the cradle body will restore the levers and dogs to the 30 position shown in Figs. 2 and 4. From the foregoing it will be seen that there is an escapement of one notch of the ratchet wheel for each stroke or vibration of the cradle body or other object being oscillated, 35 the momentum of the latter on each stroke carrying the escapement mechanism over what otherwise would be a stopping position, so that the step-by-step release continues until the spring has been completely 40 unwound or until the oscillating body has been stopped. It is further characteristic of the invention that the spring mechanism imparts positive impelling movement to lever 24 during the vibration in each direction of 45 the latter, and hence the part which is actuated—in the present instance the cradle body—is positively moved in each direction past the center. In this particular the invention is distinguished from a construction 50 wherein the impelling mechanism may be active during the vibrations in one direction of the actuated body and inactive during the vibrations in the opposite direction, in such case what may be termed the inactive vibrations being accomplished solely by the momentum of the cradle or other swinging body.

The escapement may be directly transmitted as in the adaptation shown in Fig. 6 65 or through the medium of the reducing gear-

ing shown in Fig. 1. And while the invention is designed primarily for automatically rocking a cradle, it may obviously be applied to various other uses.

I claim:

1. In an escapement mechanism, the combination of a spring-impelled ratchet wheel, a lever support, two levers each pivoted to the support and extending, respectively, toward opposite sides of the ratchet wheel, the levers connected together for simultaneous movement, and dogs carried by the levers and operated by the latter to alternately engage the wheel teeth for limiting the escapement thereof. 70
2. In an escapement mechanism, the combination of a spring-impelled ratchet wheel, a lever support, levers extending across the face of the wheel to opposite sides thereof, the levers arranged end to end with their adjacent ends jointed together and with each lever pivoted to the support adjacent to said joint, and spring-actuated dogs pivoted to the levers and adapted to be operated by the oscillations of the levers whereby the ratchet wheel is engaged by first one dog and then the other for affording step-by-step escapement. 75
3. In an escapement mechanism, the combination of a spring-impelled ratchet wheel, a lever support, two levers arranged end to end and extending to opposite portions of the wheel, the levers jointed together at their adjacent ends and each fulcrumed to the support adjacent to said joint, dogs pivoted to the levers for engaging opposite portions of the ratchet wheel, and a spring for each dog having fixed position with the free portion of the spring connected to its dog, each lever when in one position maintaining its dog and spring in such position that the dog is held in engagement with the ratchet wheel while movement of the lever from such position causes the spring to move the dog out of engagement with the ratchet wheel. 80
4. In an escapement mechanism, the combination of a spring-impelled ratchet wheel, a lever support, two levers fulcrumed to the support and with the adjacent ends of the levers connected together, dogs pivoted to the respective levers for engaging opposite portions of the ratchet wheel, a spring for each lever, each spring having fixed position with the free portion thereof loosely engaged by the lever and adapted to be deflected when the lever is oscillated, said free portion of the spring connected to the pivoted dog and adapted to turn the latter into or out of engagement with the ratchet wheel 110 determined by the direction of movement of the lever, the relative movement of the lever and spring resulting in said turning movement of the dog. 115
5. In an escapement mechanism, the com- 120

bination of a spring-impelled ratchet wheel, a lever support, two levers each fulcrumed to the support and with the adjacent ends of the levers connected together, ratchet wheel 5 engaging dogs pivoted to the respective levers, each lever having an aperture adjacent its dog, and a spring for each lever having a fixed support with the free portion of the spring extending through the lever aperture 10 and connected to the pivoted dog, each lever when oscillating adapted to laterally deflect its spring and the movement of the latter within the lever aperture operating to turn the pivoted dog mounted on such lever 15 either into or out of engagement with the ratchet wheel determined by the direction of movement of the lever.

6. In an escapement mechanism, the combination of a spring-impelled ratchet wheel, 20 a lever support, fulcrum posts projecting from the support, two levers fulcrumed, respectively, on the posts with the adjacent ends of the levers connected together and with their free portions extending to opposite portions of the wheel, reversely positioned dogs pivoted, respectively, to the levers, the pivotal movement of each dog adapted to move it either into or out of engagement with the ratchet teeth, a spring 25 arm for each lever fixed to the fulcrum post thereof with its free portion extending over the lever and loosely connected to the latter for independent lateral movement relatively thereto, the free portion of the spring connected to and adapted to oscillate the dog into or out of engagement with the ratchet determined by the direction of movement 35 of the lever.

7. In an escapement mechanism, the combination of a spring-impelled ratchet wheel, 40 two levers supported independently of the wheel and extending from the wheel center toward opposite portions thereof, the levers jointed together at their adjacent ends and 45 separately fulcrumed adjacent the joint whereby the free portion of one lever is oscillated in one direction and the corresponding portion of the other lever is similarly oscillated, reversely positioned dogs mov- 50 ably supported by the respective levers and adapted to engage opposite portions of the wheel, and means actuated by the movement of each lever for moving the dog connected to such lever either into or out of engage-

ment with the wheel determined by the direction of movement of the lever, each dog alternately engaging and disengaging the wheel simultaneously with the disengagement and engagement, respectively of the other dog. 55

8. In an escapement mechanism, the combination of a spring-impelled ratchet wheel, two levers jointed together at their adjacent ends with their free portions extending to opposite sides of the wheel, the levers separately fulcrumed adjacent their jointed ends whereby the free portions of the levers are adapted to be oscillated simultaneously, reversely acting dogs mounted on the free portions of the levers and adapted to engage 60 opposite portions of the ratchet wheel, means actuated by the movement of each lever for placing the dog carried by such lever either in or out of engagement with the wheel determined by the direction of 65 movement of the lever, and a body adapted for a back and forth movement with a connection between the body and one of the levers, the momentum of the body operating to maintain a step-by-step release of the 70 ratchet wheel through the medium of the dog-carrying levers.

9. In an escapement mechanism, the combination of a spring-impelled ratchet wheel, a lever support, two levers each pivoted to 85 the support and extending, respectively, toward different portions of the wheel periphery, means connecting the levers whereby their free portions are adapted to move simultaneously first in one direction and then 90 in the opposite direction, reversely positioned dogs pivoted to the respective levers, springs actuated by the movements of the levers for maintaining one dog in engagement with the ratchet wheel and simultaneously disengaging the other dog therefrom, whereby positive movement is imparted to one or the other of the connected levers each time the latter is oscillated, one of said levers adapted to transmit motion to a part to be 95 actuated during each beat or vibration of such lever.

In testimony whereof I affix my signature in presence of two witnesses.

FRANK MAGIDSON.
